UNITED STATES PATENT OFFICE.

NILS WINQVIST, OF TOLLARP, SWEDEN.

ROTATING KILN FOR BURNING CEMENT AND THE LIKE.

1,415,970.

Specification of Letters Patent. Patented May 16, 1922.

Application filed October 30, 1918. Serial No. 260,369.

To all whom it may concern:

Be it known that I, NILS WINQVIST, a subject of the King of Sweden, residing at Tollarp, Sweden, have invented new and useful Improvements in Rotating Kilns for Burning Cement and the like, of which the following is a specification.

It has already been proposed to provide rotating kilns for the burning of cement and the like with projections, or the like, on the walls of the preparatory heating zone, for the purpose, among other things, of giving greater heating surface. These projections, however, have been arranged as drivers or catches which have carried the material upwards in the rotation of the kiln and have then let it fall again. This has caused a considerable creation of dust which has been all the greater that, for the purpose of effective heating, the material has been as finely divided as possible. Consequently, the greater heating surface is gained in these known arrangements at the cost of a diminished output on the part of the kiln. In order to remove this inconvenience, the above-mentioned projections, etc., are so formed in accordance with the present invention, that they do not contribute to lifting the material during the rotation of the kiln. The form and arrangement of the projections, etc., can be, for example, such that the projections only cut or penetrate the material during the rotation of the kiln, and for this purpose there is preferably adopted a good heat-conducting material, such as iron, for example. They can, in addition, also be formed so that they present to the material to be burned only edges in the direction of rotation, but, in other respects, have larger surfaces which are so placed that they do not carry the material to be treated, with them in the rotation. In this way there is avoided the creation of dust and, at the same time, the material is exposed to a large heating area.

In the accompanying drawing there is shown, only as an example, a part of a cement-burning kiln constructed in accordance with the present invention. Fig. 1 shows a longitudinal section of the kiln, and Fig. 2 a transverse section through the preparatory heating zone of the kiln and nearer to the cement-feeding end of the same.

In that part of the preparatory zone

which lies at the cement-feeding end, there are arranged on the walls of the kiln which are, as usual, lined with fire-proof stone or brick, projections in the shape of gates or frames 1, of iron, for example, and open in the direction of rotation. During the rotation of the kiln the gates or frames cut through the cement but do not carry the latter with them in the rotation. In this process a great heating surface is presented to the cement without it being necessary for the latter to be carried along in the rotation and thus cause the before-mentioned creation of dust. In the drawing the gates or frames 1 are shown arranged in rows, with each row in one transverse-sectional plane, but they can, of course, be arranged in many other ways.

With a kiln of the construction shown in the drawing it has been found on experimenting, that the output of the kiln becomes unusually large and that a considerable sparing of fuel is made, all of which is plainly of great importance from an economic point of view.

The various parts in the arrangement shown can be modified in respect of material, size, shape, number, composition and arrangement, and can be reversed as long as the characteristic features of the invention are retained.

What I claim is:

1. In combination, a rotary kiln having a preparatory heating zone, and flat projections extending from the wall of said zone and leaving a free central passage in the kiln, said projections being spaced longitudinally and circumferentially of the kiln and having large surfaces parallel to the direction of rotation and presenting thin edges and open spaces to the material in the direction of rotation thereby to prevent lifting of the material by said projections during rotation.

2. In combination, a rotary kiln and a plurality of frames projecting inwardly from the inner wall of the kiln, said frames comprising spaced transversely disposed members, and longitudinal extending members connecting the latter.

In testimony whereof I have signed my name to this specification.

NILS WINQVIST.
